MERCHANDISE RACK

Herbert O. Nelson, San Rafael, Calif., assignor to International Minerals & Chemical Corporation, a corporation of New York

Application July 25, 1955, Serial No. 37,119

Term of patent 14 years

(Cl. D80—10)

FIG. 1

I claim:

The ornamental design for a merchandise rack, substantially as shown.
